(57) **CLAIM**

We claim the ornamental design for a display screen or portion thereof with icon, as shown and described.

DESCRIPTION

FIG. 1 is a front view of a display screen or portion thereof with icon showing our new design; and,

FIG. 2 is a front view of another embodiment of the display screen or portion thereof with icon.

The dot dash lines in the figures illustrate both a boundary line and a display screen or portion thereof, and form no part of the claimed design.
